UNITED STATES PATENT OFFICE.

HENRY RYDER, OF NEW YORK, N. Y., ASSIGNOR, BY MESNE ASSIGNMENTS, TO NIAGARA CORDAGE COMPANY.

SPINNING-MACHINE.

1,113,489.

Specification of Letters Patent.

Patented Oct. 13, 1914.

Application filed August 29, 1905, Serial No. 276,268. Renewed March 6, 1914. Serial No. 822,966.

To all whom it may concern:

Be it known that I, HENRY RYDER, a citizen of the United States, residing at New York, in the county of New York and State 5 of New York, have invented a new and useful Improvement in Spinning-Machines, of which the following is a specification.

My invention relates to spinning machines and more especially to machines for spinning fibers around a wire core.

The object of my invention has been to produce a machine that will spin the fibers around the wire core so that they will lie parallel to each other and so that when the 15 yarn is under tension, every fiber will bear an equal strain up to the limit of its tensile strength.

Referring now to the drawings herewith consisting of one sheet and four figures, in 20 which like characters of reference indicate corresponding parts throughout the several figures: Figure 1 is a side elevation partially in section, of my machine. Fig. 2 is a top plan view of that portion of the 25 machine which is to the right of line A—B of Fig. 1. Fig. 3 is a sectional view taken on the line X—Y of Fig. 2. Fig. 4 is an enlarged detail of my capstan mechanism.

It should be noted that my invention as 30 illustrated is composed of twin parts and thus in Fig. 2 there is shown on the front and to the left of the line C—D, a plan of the mechanism connected with the upper shaft while to the back of the said line 35 C—D, all of the upper shaft and its mechanism are broken away and the lower main shaft and its mechanism are shown.

The machine is mounted on the frame 1 which carries a driving shaft 2 upon which 40 is mounted a bevel gear 3 which meshes with the pinion 4 carried by the main shaft 5. Upon the main shaft 5 is mounted a spur gear 6 which drives gear 7 rigidly mounted on the flier 8 through the medium of the intermediate gear 9. Also mounted on the main shaft 5 is the gear 10 which through 45 the medium of intermediate gear 13, drives gear 11 which is rigidly mounted on the wire stand 12. The two trains of gears 6, 7, 9, and 10, 11, 13 are so proportioned and

placed that the flier 8 and the wire stand 12 have exactly the same speed of rotation.

Upon the wire stand 12 is mounted the wire spool 14 from which the wire leads through the hollow spindle 15; through the 55 gear 11; thence through a groove in the upper nipper roll 16; over the divider 17; through the sleeve 18; where the fiber is spun about it.

The fiber is fed through the trumpet 52 60 to the endless belt or chain 51 which carries it to the nipper rolls 16, and 50 and below the divider 17 where it enters the sleeve 18 and is then spun about the wire. The finished yarn then travels around the capstan 61 sheaves 19 and the guide sheaves 20 and then is wound upon the yarn spool 21.

The yarn spool is supported by the shaft 22 and driven by the hollow shaft 23 which receives its motion through a train of gears 70 24, 25, and 26. The gear 24 is loosely mounted on the shaft 5 and is held in frictional contact with the gear 6 by means of the spiral spring 27.

The carrier 51 is driven from the driving 75 shaft 2 by any suitable means connecting said shaft with the shaft 28. Motion is given the carrier 51 from the shaft 28, through the train of speed reducing gears 29, 30 and 31. Thus it is evident that the 80 speed of the carrier 51 is quite independent of the speed of the wire stand 12, and the flier 8. Mounted on the shaft 5 is a spur pinion 53 which meshes with a gear 32 which is carried by a bearing 33 mounted 85 in the frame 1. The bearing 33 also carries a pinion 34 which drives the gear 35 mounted on the sleeve 18, through the intermediate gear 36.

Upon the inner end of the sleeve 18 is 90 rigidly mounted a bevel gear 37 which meshes with a bevel gear 38 mounted on a stud. Mounted on the same stud, is a spur gear 39 which drives the spur gears 40. The spur gears 40 are rigidly connected 95 with the capstan sheaves 19. By means of the trains of gearing last above described I am able to give to my yarn the desired amount of draw or travel with reference to the travel of the carrier 51 and thus I am 100

able to spin any size of yarn that may be desired. Inasmuch as the yarn spool 21 is driven simply by frictional contact as hereinbefore described, its relative travel with respect to the flier is just sufficient to take up the slack of the yarn as it is delivered from the capstan sheaves 19 around the guide sheaves 20. Also mounted on the main shaft 5 is a bevel pinion 41 meshing with the bevel 42 upon the shaft 43 from which motion is transmitted to the shaft 44 by means of a bevel pinion 45 and a gear 46. The shaft 44 is a screw provided with a right and left handed thread and mounted thereon is a nut 47 whose forked end engages the collar 48 on the shaft 23. Thus by means of the train of gearing, the screw shaft, the nut, the collar and the loosely mounted shaft 23 the yarn spool 21 is given a regular longitudinal motion back and forth and the yarn is permitted to wind evenly on the spool.

Having thus described the several parts of my machine I will now describe its method of operation.

The wire spool 14 is filled with wire. The end of the wire is passed through the hollow spindle 15, over the carrier 51, through the groove in the upper nipper roll 16 and above the divider 17. The sliver fibers are at the same time passed through the trumpet 52 over the carrier 51, between the nipper rollers 16 and 50 and under the divider 17. Thence both the wire and the fibers, as a completed yarn, are carried through the sleeve 18 around the capstan sheaves 19 and the guide sheaves 20 to the yarn spool 21 to which their ends are attached. Power is applied to the driving shaft 2 and the main shaft 5 is revolved. Through the train of gearing 10, 11, and 13 the wire stand 12 is revolved and at the same time and with the same speed of rotation the flier 8 is driven by means of the train of gears 6, 7, and 9. Thus it will be evident that because the wire spool and the flier have the same speed of rotation, the wire will be delivered to the yarn spool free from any torsional twist. The sliver fibers as they are delivered from the carrier 51 lie parallel to each other. When these parallel fibers reach the sleeve 18, they are, by reason of the rapid rotation of the flier, which carries with it the capstan sheaves, given a twist that lays them still parallel in a spiral around the untwisted wire center. It should be noted that by means of the construction described the fibers are not massed into a tape formation but throughout are laid parallel to each other, and so, when put under a strain, every fiber bears, up to the limit of its tensile strength, its own share of the strain.

The speed of feed of the fiber is regulated by means of the train of gears 29, 30, and 31. While the fiber and wire are being spun

together, the resulting yarn is given any desired amount of tension and twist, by means of the train of gears 53, 32, 34, 35, and 36 and the train 37, 38, 39 and 40, it being observed that to change the speed of drive of the capstan sheaves 19 it is only necessary to remove the double-gear 32, 34, and substitute one having a different ratio. It will be understood that the rate at which the fibers are drawn from the carrier through the sleeve 18 will depend upon the speed of drive of the capstan sheaves, and that in turn, the amount of twist will depend upon the rate of drawing the fibers, since it may be assumed that the speed of rotation of the flier 8 remains constant, and the number of turns of the flier per unit movement of length of the fibers determines the degree of twist. The completed yarn is then passed around the capstan sheaves 19 and the guide sheaves 20 to the yarn spool 21 which as heretofore described is given both a rotary and a longitudinal motion.

It will be at once apparent, from the above description, to those skilled in the art that, by means of my invention, I am able to produce a yarn which, when put under strain, will carry such strain equally distributed throughout every fiber and which because every fiber lies in parallel relation to every other, will have no hollow center or core.

Having thus described my invention, what I claim is:

1. A spinning machine comprising means for feeding fiber in straight fibers, means for feeding a wire and means for spinning said fibers parallel to each other spirally around said wire.

2. A spinning machine comprising a sleeve, means for feeding a wire to said sleeve, means for feeding straight fibers to said sleeve and means for spinning said fibers spirally parallel to each other around said wire.

3. A spinning machine comprising a sleeve, means for feeding a wire to said sleeve, means for feeding straight fibers to said sleeve, means for keeping said wire and said fibers separate until they reach said sleeve and means for spinning said fibers parallel to each other spirally around said wire.

4. A spinning machine comprising a sleeve, means for feeding, separately to said sleeve, a wire and parallel fibers, means for spinning said fibers parallel to each other spirally around said wire, and means for giving to the yarn thus spun any desired amount of twist.

5. A spinning machine comprising a sleeve, means for feeding separately to said sleeve a wire and parallel fibers, means for spinning said fibers parallel to each other spirally around said wire, and means for

winding the yarn thus spun onto a yarn spool.

means for winding said yarn evenly on a
yarn spool.

6. A spinning machine comprising a sleeve, means for feeding separately to said sleeve a wire and parallel fibers, means for spinning said fibers parallel to each other spirally around said wire, means for giving any desired twist to the yarn thus spun and

10
In testimony whereof I have hereunto set
my hand in the presence of two witnesses.

HENRY RYDER.
